GOLF BAG SUPPORTING DEVICE

Filed Nov. 21, 1927

INVENTOR

G. W. LESCHER

BY *Maurice Leo.*
ATTORNEYS.

UNITED STATES PATENT OFFICE.

GEORGE WRIGHT LESCHER, OF LITTLE ROCK, ARKANSAS.

GOLF-BAG-SUPPORTING DEVICE.

Application filed November 21, 1927. Serial No. 234,804.

My invention relates to improvements in golf bag supporting devices, and it consists in the combinations, constructions, and arrangements herein described and claimed.

5 An object of my invention is to provide a golf bag supporting device which may be readily secured to any size or type of golf bag for supporting the same.

A further object of my invention is to provide a device of the type described which has novel means for automatically actuating supporting members when the golf bag is placed upon the ground so that the supporting members will hold the golf bag in a substantially 15 upright position.

A further object of my invention is to provide a device of the type described which has novel means for automatically moving the supporting members into their normal positions when the golf bag has been raised from the ground.

A further object of my invention is to provide a device of the type described which holds the golf bag at a desired angle for 25 readily removing the golf sticks.

A further object of my invention is to provide a device of the type described which prevents the golf bag from collapsing or sagging when placed on end.

30 Other objects and advantages will appear in the following specification, and the novel features of the invention will be particularly pointed out in the appended claims.

My invention is illustrated in the accompanying drawings, forming part of this application, in which

Figure 1 is a top plan view of the device,

Figure 2 is a bottom plan view of the device, parts thereof being shown in section,

40 Figure 3 is a section along the line 3—3 of Figure 1,

Figure 4 is a section along the line 4—4 of Figure 1,

45 Figure 5 is a section along the line 5—5 of Figure 1,

Figure 6 is a top plan view of a portion of the device,

50 Figure 7 is a side elevation of that shown in Figure 6,

Figure 8 is a side elevation of the device as applied to a golf bag, and

Figure 9 is a rear elevation of the device as applied to a golf bag.

In carrying out my invention, I provide a 55 casing 1 which is somewhat arcuate-shaped in general contour. The casing 1 is provided with an arcuate-shaped compartment 2 which communicates at its ends with transversely extending compartments 3 and 4 and at its 60 center with a guide receptacle portion 5. Elongated grooves 6 are provided in the walls of the receptacle 5.

A movable frame 7 which is arcuate-shaped in general contour is arranged to be disposed 65 in the arcuate-shaped compartment 2. The ends of the frame 7 are provided with rack portions 8 and 9, the teeth of which extend into the transversely extending compartments 3 and 4, respectively. The frame 7 is provided with a guide 10 positioned at its center and arranged to be disposed in the guide receptacle 5. The guide 10 is provided with 70 tongue portions 11 upon each side thereof and arranged to be received in the grooves 6. 75

The guide 10 is provided with a reduced collar portion 12 and a central opening 13 which is arranged to receive an actuating rod 14. The rod 14 is rigidly held in place by a bolt 15 or the like. The upper surface of the 80 guide 10 is provided with a circular recess 16 for receiving a cone-shaped spring 17 which is disposed between the guide 10 and the casing 1.

Supporting members or tubes 18 are provided 85 at their upper ends with toothed lever arms 19 which are pivotally disposed in the transversely extending compartments 3 and 4 in such a manner that the teeth 20 thereof are in mesh with the teeth of the rack portions 8 and 9. The lower extremities of the supporting members or tubes 18 and the rod 20 are provided with resilient pads 21.

The casing 1 is provided with substantially U-shaped bag-receiving portions 22 which 95 are provided with arcuate-shaped gripping surfaces 23 having arcuate-shaped recesses 24 therein. Clamps or gripping members 25 are provided with arcuate-shaped recesses 26 and arranged to be adjustably secured in the 100

substantially U-shaped portions 22 by means of bolts 27. The bolts 27 extend through elongated slots 28 and openings 29 which are provided in the flanges 30 which are integral 5 with the gripping members 25. Adjusting screws 31 extend through the casing 1 and have their ends receivable in recesses 32 in the gripping members 25. The adjusting screws 31 may be locked in adjusted position 10 by lock nuts 33.

A base 34 is provided with members 35 and 36 which have gripping lugs 37 and 38 extending transversely with respect thereto. The members 35 and 36 are adjustably secured to each other by a bolt 39. The member 35 is provided with a bearing portion 40 having an opening 41 therethrough arranged to receive the actuating rod 14.

From the foregoing description of the various parts of the device, the operation thereof may be readily understood. The ordinary golf bag, such as that indicated at 42, is provided with a beaded top 43 and a rigid bottom portion 44. The arcuate-shaped gripping 20 surfaces 23 are so arranged that the casing 1 may be readily disposed upon the golf bag 42 and rigidly secured in place in the following manner. The substantially U-shaped bag-receiving portions 22 of the casing 1 are disposed over the beaded top 43 of the golf bag 42 in such a manner that the arcuate-shaped gripping surfaces 23 thereof will be positioned against the inner wall of the golf bag. The clamps or gripping members 25 may then be moved into gripping relation with the bag so that the beaded top 43 will be received in the recesses 24 and 26. This moving of the gripping members 25 is done by actuating the adjusting screws 31. The adjusting screws may be locked in the desired 25 positions by the lock nuts 33 which engage with the inner wall of the casing 1. The clamps or gripping members 25 may be further locked in their gripping positions by 30 making tight the bolts 27.

The base 34 may be disposed upon the bottom portion 44 of the golf bag so that the gripping lugs 37 and 38 engage with the bottom portion 44 when the members 35 and 50 36 are drawn together by means of the bolt 39.

The spring 17 will hold the supporting members 18 in close engagement with the golf bag while the golf bag is being carried. If 55 the user is desirous of placing the golf bag upon the ground in a substantially upright position, by placing the golf bag so that it will presumably set upon the bottom portion, the actuating rod 14 will engage with 60 the ground. As the actuating rod engages with the ground, the weight of the golf bag and the contents thereof is sufficient to actuate the rod 14 against the tension of the spring 17 for moving the frame within the 65 casing 1 in such a manner that the guide

10 and the tongue portions 11 will move within the receptacle 5 and the grooves 6. The upward movement of the frame 7 causes the supporting members 18 to swing outwardly, due to their operative engagement 70 with the frame through the rack portions 8 and 9 and the toothed portions 20 of the lever arms 19. Therefore, it will be observed that immediately upon placing the golf bag upon the bottom portion, the supporting 75 members 18 will be automatically swung outwardly to form a tripod with the actuating rod 14 for supporting the golf bag.

As soon as the golf bag is raised free from the ground, the spring 17 moves the frame 80 7 downwardly causing the toothed connection between the frame and the supporting members to automatically swing the supporting members into their normal positions adjacent the golf bag. 85

I claim:

1. A device of the type described comprising a casing having means for removably clamping said casing onto a golf bag, a frame movably disposed within the casing and being provided with ratchet teeth, a plurality of supporting members having teeth for engaging the ratchet portion of said frame, and an actuating rod having one end operatively connected with said frame and the opposite end projecting beyond the bottom of the bag. 90

2. A device of the type described comprising a casing having means for removably clamping said casing onto a golf bag, a frame movably disposed within the casing and being provided with ratchet teeth, a plurality of supporting members having teeth for engaging the ratchet portion of said frame, an actuating rod having one end operatively 100 connected with said frame and the opposite end projecting beyond the bottom of the bag, and means removably attached to the bottom of the bag for slidably guiding said actuating rod. 105

3. A device of the type described comprising a casing having means for removably clamping said casing onto a golf bag, a frame movably disposed within the casing and being provided with ratchet teeth, a plurality 115 of supporting members having teeth for engaging the ratchet portion of said frame, an actuating rod having one end operatively connected with said frame and the opposite end projecting beyond the bottom of the bag, means removably attached to the bottom of the bag for slidably guiding said actuating rod, and spring means disposed within the casing and bearing against said frame. 120

4. A device of the type described comprising a casing having arcuate-shaped portions for engaging a portion of the upper edge of a golf bag, arcuate-shaped gripping members carried by the casing for clamping a portion of the upper edge of the bag between the arc- 125 130

- uate-shaped surfaces and said gripping members, a frame movably disposed within the casing and being provided with ratchet teeth, a plurality of supporting members having teeth for engaging the ratchet portions of said frame and pivotally mounted therein, spring means disposed within the casing and bearing against said frame for normally holding the lower edge of the frame substantially flush with the lower edge of the casing, and an actuating rod having one end operatively connected with said frame and the opposite end projecting beyond the bottom of the bag.
- 5 5. A device of the type described comprising a casing having arcuate-shaped portions for engaging a portion of the upper edge of a golf bag, arcuate-shaped gripping members carried by the casing for clamping a portion of the upper edge of the bag between the arcuate-shaped surfaces and said gripping members, a frame movably disposed within the casing and being provided with ratchet teeth, a plurality of supporting members having teeth for engaging the ratchet portions of said frame and pivotally mounted therein, spring means disposed within the casing and bearing against said frame for normally holding the lower edge of the frame substantially flush with the lower edge of the casing, an actuating rod having one end operatively connected with said frame and the opposite end projecting beyond the bottom of the bag, and means clamped upon the bottom of the bag for slidably guiding said actuating rod.
- 10 6. A device of the type described comprising a casing having means for removably clamping said casing onto a golf bag, a frame movably disposed within the casing and being provided with ratchet teeth, a supporting member pivotally secured to the casing and having teeth arranged for engaging said ratchet teeth, and an actuating rod having one end operatively connected with said frame and the opposite end projecting beyond the bottom of the bag, whereby movement of the actuating rod upwardly with respect to the bag will cause said supporting member to be moved into a supporting position.
- 15

Signed at Tampa, in the county of Hillsborough and State of Florida, this fifteenth day of November, A. D. 1927.

55 GEORGE WRIGHT LESCHER.
